Primary Examiner — Susan Bennett Hattan*Assistant Examiner* — Marie D. Fast Horse(74) *Attorney, Agent, or Firm* — Christensen O'Connor Johnson Kindness PLLC(57) **CLAIM**

An ornamental design for a computer input device, as shown and described.

DESCRIPTION

FIG. 1 is a right side front perspective view of a computer input device showing my new design;

FIG. 2 is a top plan view thereof;

FIG. 3 is a bottom plan view thereof;

FIG. 4 is a front elevation view thereof;

FIG. 5 is a back elevation view thereof;

FIG. 6 is a left elevation view thereof; and,

FIG. 7 is a right elevation view thereof.

The broken lines in the drawings depict portions of the computer input device that form no part of the claimed design.

1 Claim, 5 Drawing Sheets(56)
